(57) CLAIM

The ornamental design for a four-pack carrying device, as shown and described.

DESCRIPTION

FIG. 1 is a front elevational view of a four-pack carrying device of the present design;

FIG. 2 is a side elevational view thereof;

FIG. 3 is a top plan view thereof;

FIG. 4 is a bottom plan view thereof; and,

FIG. 5 is a perspective view thereof with bottles inserted.

The broken line showing of stitching and a handle opening is for illustrative purposes only and form no part of the claimed design.
